UNDER-MATTRESS

Roland Schmutz, Hauptstrasse 13 (Aargau),
Zofingen, Switzerland

Filed Nov. 17, 1959, Ser. No. 853,483

Claims priority, application Switzerland Nov. 20, 1958
7 Claims. (Cl. 5—361)

This invention relates to an under-mattress of a construction which obviates the use of metallic springing means.

It is the principal object of the invention to provide an under-mattress which has a well balanced springing resistance over the entire supporting surface as far as the edge in order to prevent the channel-like local depression appearing in hitherto known under-mattresses in the regions exposed to the greatest stress in normal use.

Another object of the invention consists in the provision of an under-mattress including means for permitting a sufficient ventilation without impairing the adequate heat damping.

Further objects residing in details of construction will be apparent from the following specification and claims.

In the accompanying drawing which illustrates one embodiment of the invention,

FIG. 1 is a plan view of the view of the under-mattress with the upper part partly broken away, and

FIG. 2 shows a vertical longitudinal section through the under-mattress lying on a frame with legs.

The under-mattress illustrated lies on a frame 3 provided with four legs 1 and cross-pieces 2, and is subdivided into independently rockable parts serving as a body support 4 and head rest 4', each of which is provided with a stable base plate 5 and 5' respectively which are preferably made of plywood and on which a pressure-elastic intermediate filling of uniform thickness, for example of porous rubber, is fastened, preferably by adhesion. This filling is composed of strips in such a way that within an edge 6 and 6' respectively closed around its edges, air chambers 7 and 7' respectively are provided in a practically regular distribution, these air chambers being separated from one another by filling strips 8 and 8' respectively lying in the longitudinal direction of the mattress. An elastically flexible, plate-shaped upper part 9 and 9' respectively, preferably of thin laminated plywood is glued on the intermediate filling and is subdivided by transverse slits 10 and 10' respectively into juxtaposed partial plates 11 and 11' respectively, the various adjoining partial plates being joined on their underside beneath the slit by means of a fabric strip 12 which is permeable to air. The air chambers 7 and 7' respectively are ventilated in the upward direction through these transverse slits 10 and 10' respectively and in the downward direction by holes 14 and 14' respectively in the base plates 5 and 5' respectively, these holes being covered by pieces of fabric 13 permeable to air, while the fabric coverings 12 and 13 prevent the penetration of dust and protect the air chambers 7 and 7' against external air circulation, so that the chambers serve as insulation.

In the middle region which is exposed to the greatest load during normal use of the under-mattress, the intermediate filling has in the middle air chambers 7 intermediate strips 15 of the same material for the closer supporting of the upper part 9.

The body support 4 which can be swung up at the foot end, and the head support 4' which can also be swung up are supported in the manner of a joint in a suitable cross-piece 18 having the profile of a hollow arc of a circle on the frame 3, along a transverse slit 16 between the upper parts 9 and 9', by means of bars 17 and 17' respectively having the profile of an arc of a circle and fastened on

2

the underside of the respective base plate 5 and 5'. At the joint between the head rest 4' and the body support 4 the geometrical turning axis runs along the slit 16.

The transverse slits 10 and 10' of the plate-shaped upper parts need not extend to the edges on both sides, but can end at a certain distance from the same. The under-mattress can be constructed in one piece over the entire length without sub-division into head and body support.

In consequence of its special construction which obviates the use of metallic springing means, the under-mattress described with the elastically stiff, plate shaped upper part has a well balanced springing resistance over the entire supporting surface as far as the edge, while in the case of under-mattresses of the type hitherto customary this resistance increases greatly from the middle towards the usually rigid edges and has the consequence that the resting body of the user unintentionally tends to slip towards the middle. In contradistinction thereto, the supporting surface of the under-mattress according to the invention can be effectively used over the full width and can therefore be narrower.

Particularly when using an upper-mattress having in itself adequate local elasticity, the ability of the plate-shaped upper part to bend as a surface, in the case of the object 25 of the present invention, leads to the combination result that the body of the user, lying on his back, is supported not only at the anatomically predetermined resting parts which are in the nature of centres of gravity, namely the buttocks and the shoulder blades, but also at all other 30 parts of the back and of the backs of the thighs, whereby the anatomically correct position of rest of the body is ensured, but in addition the continuous supporting of the back and the relieving of the same from loads, which are important for the relaxation of the muscles, between the 35 supporting parts acting as centres of gravity are achieved.

The construction of the under-mattress described, with air chambers, serves to dam up heat and also appropriately to provide ventilation, since the upper and lower ventilation apertures are covered by pieces of fabric permeable to air, in order that the air contained in the chambers shall not participate in the free circulation of the outer air, but shall partially pass out and be replaced by suction only in accordance with the variations of the chamber volumes resulting from the loading and unloading of 45 the mattress. Since the upper slit-like openings are considerably larger than the bottom openings, ventilation also takes place in the upward direction towards the upper mattress, thereby preventing condensation of moisture emanating from the perspiration of the body. In addition, "breathing" also takes place in the intermediate filling, which preferably consists of porous rubber, in consequence of the compression and expansion.

It is understood that the under-mattress described can also be suspended without feet in one of the hitherto customary bedsteads.

What I claim is:

1. An under-mattress comprising a stable base plate adapted to be supported by a frame having legs, a plate-like upper part which is elastically flexible and forms a substantially flat support surface for any desired type of upper-mattress, and a pressure-elastic intermediate filling supported by said base plate and carrying said upper part, said intermediate filling having an endless edge portion extending between the peripheries of said base plate and upper part and being formed inwardly of said edge portion with a plurality of air chambers, said upper part being subdivided by transverse straight slits into separate strips which have each a plate-like elastical stiffness and form together said support surface, fabric strips joining adjacent strips forming said upper part, said fabric strips being permeable to air and covering each one of said slits

along the whole length on the side of said intermediate filling and said air chambers, said base plate having a plurality of restricted apertures, fabric pieces which are permeable to air covering each one of said apertures on the side of said air chambers, said fabric strips and pieces permitting circulation of air through said slits and apertures upon compression or tension release of said under-mattress.

2. An under-mattress as claimed in claim 1, wherein the plate-like upper part is laminated and thin in construction and consists of plywood.

3. An under-mattress as claimed in claim 1, wherein the intermediate filling is constituted by strips of porous rubber which are fastened at least to the base plate and form the endless edge portion of said base plate as well as intermediate strips extending in the longitudinal direction of said under-mattress from edge to edge for limiting therewith the air chambers and strips disposed within said air chambers for the closer supporting of the upper part in regions of said filling exposed to the greatest stress in normal use.

4. An under-mattress as claimed in claim 1, wherein the body of said under-mattress is transversely subdivided to form a head end constructed to be swung up and supported in a manner of a joint in the form of an arc of a circle, along a cross slit of the plate-like upper part of means of a bar having the profile of an arc of a circle.

5. An under-mattress comprising, in combination, a base plate; an upper cover part formed from a plurality of thin plates each formed from elastically deformable material, said plates extending in transverse direction of said under-mattress and being separated from each other by small gaps, and fabric strips of air permeable material extending over said gaps and joined to said plates along adjacent edges thereof; and an elastically compressible intermediate filling supported on said base plate and carrying said upper cover part, said intermediate filling having an endless edge portion extending between the peripheries of said base plate and upper cover part and being formed inwardly of said edge portion with a plurality of air chambers extending between said base plate and upper cover part in a direction transverse to said gaps.

6. An under-mattress comprising, in combination, a base plate; an upper cover part formed from a plurality of thin plate portions formed from elastically deform-

able material, said plate portions extending in transverse direction of said under-mattress and being separated from each other by small gaps, and fabric strips of air permeable material extending over said gaps and joined to said plate portions along adjacent edges thereof; and an elastically compressible intermediate filling supported on said base plate and carrying said upper cover part, said intermediate filling having an endless edge portion extending between the peripheries of said base plate and upper cover part and being formed inwardly of said edge portion with a plurality of air chambers extending between said base plate and upper cover part in a direction transverse to said gaps.

7. An under-mattress comprising a stable base plate adapted to be supported by a frame having legs, a plate-like upper part which is elastically flexible and forms a substantially flat support surface for any desired type of upper-mattress, and a pressure-elastic intermediate filling supported by said base plate and carrying said upper part, said intermediate filling having an endless edge portion extending between the peripheries of said base plate and upper part and being formed inwardly of said edge portion with a plurality of air chambers, said upper part being subdivided by transverse straight slits into plate portions which have an elastically stiffness and form together said support surface, fabric strips joining adjacent plate portions forming said upper part, said fabric strips being permeable to air and covering each one of said slits along the whole length on the side of said intermediate filling and said air chambers, said base plate having a plurality of restricted apertures, fabric pieces which are permeable to air covering each one of said apertures on the side of said air chambers, said fabric strips and pieces permitting circulation of air through said slits and apertures upon compression or tension release of said under-mattress.
